DESIGN FOR A DRESS

Sadie Elmo, New York, N. Y.

Application December 23, 1940, Serial No. 97,589

Term of patent 3½ years

To all whom it may concern:

Be it known that I, Sadie Elmo, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view of Fig. 1, and

Fig. 3 is an enlarged fragmentary view of the dress shown in Fig. 1 with the collar in closed

position, having one of the flaps raised and showing the integral yoke and front panel in detail.

The characteristic feature of my design resides in the combination on the striped dress disclosed of the integral, horizontally striped yoke and front panel, in association with the matching panels on the sleeves, and buttons arranged along one side of the panels, all as shown.

I claim:

The ornamental design for a dress, substantially as shown and described.

SADIE ELMO.
